UNITED STATES PATENT OFFICE.

GÜNTHER MEYER-JAGENBERG, OF DUSSELDORF, GERMANY.

PAPER-ROLL WRAPPING MACHINE.

Application filed April 7, 1927, Serial No. 181,697, and in Germany January 19, 1926.

This invention refers broadly to the application of a protecting and enveloping wrapper to large rolls of paper and similar flexible material for shipping purposes and the like, and it is particularly intended to facilitate the application of the wrapper to the roll, to reduce the amount of handling and to more securely attach the wrapper to the roll than heretofore. The devices for the wrapping up of large rolls of paper and the like for shipping or transportation purposes in which the rolls to be handled are carried upon supporting rollers and are enveloped by their own rotation with a glued web of paper or the like which is pulled off a supply roll, as constructed according to the previous art, require the employment of special heavy lifting means for the raising of the heavy rolls into the operating position and for the lowering of the wrapped up rolls. Moreover, the wrapping and discharging devices heretofore known are objectionable on account of the high, difficultly controllable and much space consuming structure. Their operation is complicated and requires much time and power. Now, it is one of the important objects of this invention to provide means for the purpose referred to in which the inconveniences mentioned in connection with the handling and wrapping up of large rolls of paper and the like are avoided. In accordance with the structure of this invention the entire combination of driving means, winding-off and gluing means is disposed below the working table or machine table which is on a level with the winding means, and the raising of the rolls to be wrapped up into the working position is effected simultaneously with the letting down of the wrapped-up rolls and by the utilization of the weight of these rolls. By this means a very compact and space-saving structure becomes possible and it also results in a great simplification of manipulation with a minimum of effort, and in a more rapid, highly economical mode of operation.

The invention will be more fully and accurately described by reference to the accompanying drawing showing by way of exemplification an embodiment of the principles of the invention in Figure 1 in side view and in Figure 2 in top plan view.

As shown in the drawing, the wrapping or packing paper roll 2 is rotatably disposed underneath the machine table 1. From this

roll 2 the web of paper is conducted through the gluing device 3 and over the guide rollers 4 to the otherwise well known supporting rollers 5 for the roll of paper 6 to be wrapped up which is rotated by a driving pulley 7, and by its rotation causes the web of wrapping paper placed against it to be wrapped around the roll 6. The wrapping web is wider than the roll 6 and the projecting portion 8 is turned down upon the front sides of the roll 6 simultaneously with the wrapping operation or subsequently thereto. At the rear of the supporting rollers 5 the machine table carries a pressing device for the wrapped-up rolls, which comprises substantially the pressing plates 9 one of which may be forced against the roll by means of a screw spindle 10. Upon the supporting posts 11 a rocking frame 12 is mounted which preferably surrounds the entire device and which, at the front and rear ends of the same, is provided with substantially arc-shaped grates or open trellis work roll supporting platforms 13, 14. The curvature of the grates or platforms 13, 14 is such that the ascending and descending surfaces formed by said platforms in this lowered and raised positions respectively will be on a level with the floor or other horizontal bottom surface and the surface of the machine table.

The mode of operation of the device is substantially as follows: The roll of paper or the like 6 to be wrapped up is pushed or rolled along the floor in the direction of the arrow indicated in Figure 1 and will thereby get upon and ascend the lowered platform grating or trellis 13. Then a previously wrapped-up roll 6 is rolled from the table 1 upon the platform grating or trellis 14, whereupon the rocking frame 12 is tilted without any effort into the position indicated in dotted lines. The then raised unwrapped roll 6 will now be pushed without any trouble or effort onto the supporting rollers 5, wherefrom the previously wrapped roll 6 has been discharged, and the rocking frame is restored to its initial position. After the glued web of wrapping paper has been placed against the roll 6 and the starting of the pulley 7 or other driving means causing the rotation of the supporting rollers 5 the roll 6 is wrapped-up and the projecting side edges of the wrapping paper are turned down upon the roll. Thereupon the roll 6 is carried between the pressing

plates 9 where the turned over portion of the wrapping paper are forced tightly against the sides of the roll. If desired, any special round-cut protecting paper caps 5 15 may be pasted onto the front sides of the finished roll. In the meantime another unwrapped roll 6 has been pushed upon the grating 13 and the cycle of operations is then repeated, the wrapped-up roll having 10 been rolled onto the grating 14. Thus a continuous operation is obtained, inasmuch as the rolls to be wrapped-up, as distinguished from the known mode of procedure, are continuously rolled onto the rocking frame in 15 the same direction, and are subsequently carried along to the different working stations and are rolled off after treatment.

It should be understood that the example described in the specification is merely illustrative and is not to be regarded as limiting the invention to this particular embodiment, but alterations and modifications may occur to suit existing conditions and the convenience of the operator without deviating from 25 the spirit of the invention, except as otherwise stated in the appended claims.

I claim:

1. In a device of the kind described in combination, elevated means for supporting 30 and rotating a roll about which flexible material is to be wrapped, means arranged at a lower level than said roll supporting means for supporting and guiding wrapping material into contact with said roll about which 35 such material is to be wrapped, and a rockable lever-like support, pivoted intermediate its ends, and adapted for respectively supporting a roll to be wrapped and a roll which has been wrapped at its opposite ends 40 and for respectively raising and lowering the said rolls into and out of cooperative relationship with respect to the elevated supporting means.

2. In a device of the kind described in combination, elevated means for supporting 45 and rotating a roll about which flexible material is to be wrapped, means for supporting and guiding wrapping material to said roll, a rocking frame, fulcrumed intermediate its ends, and curved platforms at the ends of 50 said frame, adapted to aline with the elevated supporting means in the tilted positions of the rocking frame and adapted to respectively raise and lower unwrapped and wrapped up rolls into and out of engagement with the elevated supporting means.

3. In a paper roll wrapping machine, a table, rolls disposed adjacent one end of the table for supporting and rotating a roll to be wrapped, means arranged below the level 60 of the table and rolls for supplying and guiding material to be wrapped about said roll, and a tilting frame having terminal roll supporting portions movable by the tilting 65 motions of the frame into and out of registry with the supporting and rotating rolls and the end of the table opposite said roll.

4. In a paper roll wrapping machine, a table, rolls arranged adjacent to one end of said table for supporting and rotating a 70 paper roll to be wrapped, means arranged below the level of the table for supplying and guiding material to be wrapped about said roll, a tilting frame having terminal roll supporting portions movable by the tilting 75 movements of the frame into and out of registry with the paper roll supporting and rotating rolls and the end of the table opposite said rolls, and means arranged in the path of a wrapped paper roll traveling over 80 the table for compressing projecting portions of the wrapping material against the ends of the paper roll.

In testimony whereof I affix my signature.

GÜNTHER MEYER-JAGENBERG.
